UNITED STATES PATENT OFFICE.

WILLIAM L. BEALL, OF ALBION, MICHIGAN, ASSIGNOR TO GALE MANUFACTURING COMPANY, OF ALBION, MICHIGAN.

ADJUSTING MECHANISM FOR PLOW-BEAMS.

979,366.

Specification of Letters Patent. Patented Dec. 20, 1910.

Application filed August 21, 1909. Serial No. 513,988.

To all whom it may concern:

Be it known that I, WILLIAM L. BEALL, citizen of the United States, residing at Albion, in the county of Calhoun and State 5 of Michigan, have invented certain new and useful Improvements in Adjusting Mechanism for Plow-Beams; and I do hereby declare the following to be a full, clear, and exact description of the invention, such as 10 will enable others skilled in the art to which it appertains to make and use the same.

My present invention relates to the construction of plows and more particularly to plows in which an iron or steel beam is employed, and consists in an improved means 15 for adjusting the beam to regulate the width of the furrow or to change the position of the plow with respect to the point of draft.

The principal parts of the plow shown 20 in the drawings are a land side 1 and a share 2 brought together and secured to a frog 3, pressed or drop forged into the proper form to receive the other parts. The beam A is also secured to this frog in this 25 instance by bolts a, a' one at least passing through the land side, frog and beam. They may pass through the frog and beam alone but by having one or more passing through the land side act to secure the land side and 30 frog together. In this construction it will be seen that the beam is secured to the plow parts within the hollow of the plow or in rear of the main earth engaging surfaces.

It is often desirable to adjust the plow 35 for varying width of cut or to properly aline it in respect to the point of draft. For instance, in using three horses the point of draft is farther from the land edge of the previous furrow than when two horses 40 are employed to draw the plow. It is found desirable to adjust the plow to these and other changing conditions by varying the position of the beam.

In the accompanying drawings I have 45 illustrated the best form in which I have contemplated embodying my said invention and the said invention is disclosed in the following description and claims.

In the said drawings, Figure 1 is a top 50 or plan view of a plow, one adjustment of the beam being indicated in dotted lines. Fig. 2 is a longitudinal vertical section of Fig. 1 looking toward the land side of the

plow. Fig. 3 is a horizontal section on line 3—3, Fig. 2. Fig. 4 is a like section of a 55 modified construction.

In the construction shown in Figs. 1, 2 and 3 I accomplish the change in position of the beam by means of two levers c, c' pivoted on the frog of the plow adjacent 60 to and slightly in rear of the rear edge of the beam.

The forwardly extending portions of the levers c, c' are wedging in form, as shown at c² in Fig. 2 and are adapted to be moved 65 or forced between the rear edge of the plow beam and the metallic part to which it is secured. The rearwardly extending portion of the upper lever c' is extended and formed into a handle that can be readily grasped 70 by the hand to move the levers into or out of position and on the same side of their pivots the levers are preferably connected by the link d. By this construction the two levers c, c' can be moved together by 75 the handle a².

The beam is normally secured to the plow by the bolts a, a' clamping it tightly against the inner side of the frog which is its position when the plow is drawn by two horses. 80 When it is desired to change the plow to accommodate it to the draft of three horses, the nuts on the bolts a, a' are loosened, then by grasping the outer end of the lever c', the two levers c, c' are turned, forcing the 85 wedging ends of the levers between the beam and the part to which it is secured. The nuts on bolts a, a' are then tightened and the beam rigidly secured. As the ends c² of the levers c, c' extend only a short distance be- 90 neath the beam, when the bolts a, a' are tightened the forward end of the beam will be swung to the left and will be held tightly in place. When the levers c, c' are moved to the position shown in Fig. 3 the beam will 95 be in the position for use with three horses. To change the beam back to its original position, the operation described, is reversed. By moving the levers c, c' a less distance, an 100 adjustment to a lesser degree is secured.

In Fig. 4 I have shown a construction in which the position of the beam is varied by set screws d, d' passing through threaded openings or eyes e, e' secured to or forming a part of the beam. The adjustment is 105 brought about by loosening the bolts a, a'

and then turning the set screws d, d' to cause the rear edge of the beam to take the position desired.

The securing of the adjusting devices to the frog to engage the rear edge of the beam or by securing them to the beam to engage the frog is of decided advantage as the landside may become broken or so worn as to necessitate its removal and the placing of a new part in its place. With my construction this is done without any disturbance of the parts for securing the beam adjustment.

What I claim and desire to secure by Letters Patent is:—

15 1. In combination with the furrow forming parts of a plow, of a metallic beam secured to one of the furrow forming parts in rear of the main body of said parts, and a metallic device movably mounted adjacent to said beam and adapted to be moved into and out of position to vary the angle of the beam to the part of the plow to which it is attached.

2. In combination with the earth engaging parts of a plow, of a metallic beam secured in the hollow in rear of the said earth engaging parts against the metal forming one side of said hollow and a metallic device movably mounted adjacent to said beam and adapted to be moved into and out of position to vary the angle of the beam to the part to which it is attached.

3. In a plow, the combination with the furrow forming parts and a frog to which they are secured, of a metallic beam secured to said frog in rear of the earth engaging surfaces of the furrow forming parts and a metallic device movably mounted on one of said parts and adapted to be moved into and out of position to adjust the angular portion of the beam to vary the position of the plow in respect to the point of draft.

4. In a plow, the combination with the furrow forming devices and a frog to which they are secured, of a metallic beam secured

to said frog and a metallic device movably mounted on one of said parts and adapted to be moved into and out of position between an edge of the beam and an adjacent part to vary the position of the plow in respect to the point of draft.

5. In a plow, the combination with the furrow forming parts and frog, of a metallic beam secured to said frog and a metallic device movably mounted on said frog having wedging portions adapted to be moved into and out of position between an edge of the beam and the said frog.

6. In a plow, the combination with the furrow forming parts and a frog, of a metallic beam secured to said frog and levers each having a wedging portion, said levers being adapted to be turned to place the wedging portion between the rear edge of the beam and an adjacent part to vary the position of the beam.

7. In a plow, the combination with the furrow forming parts and frog, of a metallic beam secured to said frog and a movable device pivotally mounted upon said frog and adapted to be moved into a position to increase or decrease the distance between said frog and one edge of said beam.

8. In a plow the combination with the furrow forming devices and frog, of a metallic beam secured to said frog in rear of the main earth engaging surfaces of the furrow forming devices and devices movably secured to one of said parts, said devices being adapted to engage an adjacent part at two separated points to vary the angular position of the beam for the purpose of adjusting the plow with respect to the point of draft.

In testimony whereof I affix my signature, in the presence of two witnesses.

WILLIAM L. BEALL.
